TONJES A. BOTH, OF STRATFORD, CONNECTICUT, ASSIGNOR TO THE CONNECTICUT ELECTRIC MANUFACTURING COMPANY, OF BRIDGEPORT, CONNECTICUT, A CORPORATION OF CONNECTICUT.

ATTACHMENT PLUG.

Application filed July 26, 1921. Serial No. 487,650.

To all whom it may concern:

Be it known that I, TONJES A. BOTH, a citizen of the United States, residing at Stratford county of Fairfield, State of Connecticut, have invented an Improvement in Attachment Plugs, of which the following is a specification.

This invention relates to an attachment plug and has for an object to provide a plug of this type which will be simple in construction and comprise comparatively few parts.

Another object of the invention is to provide improved means for securing the elements of the plug in assembled relation.

With these and other objects in view I have devised the improved plug illustrated in the accompanying drawings in which;

Fig. 1 is an elevation of the usual jack blade plug adapted to be used with my improved plug;

Fig. 2, a longitudinal section of my improved plug;

Fig. 3, a perspective view of the insulating body member thereof;

Fig. 4, a perspective view of the insulating button;

Fig. 5, a longitudinal section taken at substantially right angles to that of Fig. 2 and showing my preferred construction;

Fig. 6, a section similar to Fig. 5 showing a modified construction;

Fig. 7, a perspective of one of the contact elements;

Fig. 8, a perspective of the other contact element used with the form shown in Fig. 5;

Fig. 9, a perspective of a contact element similar to Fig. 8 showing a slight modification thereof adapted for use in the plug shown in Fig. 6; and

Fig. 10 is a detailed view of the screw shell.

The body member 15 of the ordinary plug is provided with the spaced contact blades 16 adapted to be inserted in the slots 17 and 18 in my improved plug. The wires 19 connected with the blades 16 lead to any desirable fixture. Slots 17 and 18 extend longitudinally of an insulating body member 20. The other end of the body member is provided with a shoulder or ledge 21 surrounding a central projection 22. In the

preferred construction hollow securing members or bushings 23 are molded in the body member, as shown in Fig. 5, the ends thereof 55 extending above the surface of the ledge 21, as shown in Fig. 3. An open-ended, threaded shell 24 is provided with an inverted flange 25 which has openings therein adapted to fit over the ends of the securing 60 members 23. Also fitting over the ends of these members 23 and within the screw shell is a segmental portion 26 of the contact member and the ends of the members 23 are spun over the top of this member, as at 27 in 65 Fig. 5, thus securing this contact member and the screw shell upon the ledge 21 of the body member. A U-shaped spring contact element 28 is secured to the segment 26 and extends into the slot 18. 70

Secured in the outer end of the shell 24 is an insulating button 29, this button being provided with a shoulder 30. On the outer wall thereof and at its inner end is a transverse channel 31, which channel extends from a point on one side of the center to within a short distance of the outer wall thereof. Extending through a longitudinal opening in the button is a central contact member 32. This member extends beyond 80 the surface of the button at its outer end and is spun over at its inner end to secure, in the recess 31, a flat contact spring 33, this spring being bent at right angles and extending into the slot 17 in the body member 20. 85

In assembling, the contact spring 33 is secured in position by the central contact 32. The screw shell 24 and the contact 28 is mounted on the body member 20 as described above. The button 29 is now inserted within open end of the screw shell 24 with the contact spring 33 extending into the slot 17 and the inner end of the button resting against the end of the projection 22. 95

The outer end of the shell 24 is now flanged or spun over the shoulder 30 as shown at 34. This securely retains the button in position and the spring 33 being set in the recess 31 prevents the button turning within the shell, should it become loose at retaining means 30—34. The contact springs 28 and 33 are provided with struck-up portions 35 adapted to extend into 100

openings 36 formed in the contact blades 16 when the same are inserted in the slots 17 and 18 and co-act therewith to tend to retain these blades within the slots and offer 5 resistance to the withdrawal thereof.

In the modification shown in Figs. 6 and 9, the shell 24 and the contact 28 are secured to the body-member 37 by means of countersunk screws 38, these screws being threaded 10 into the segmental portion 39, the holes therefor being drawn up, as shown at 40, to increase the length of the tapped hole to receive the screws 38. Otherwise, the structure of this modified form is the same as 15 that disclosed in Figs. 2 to 5 inclusive.

It will be apparent from the above that the device is simple in construction, comprises comparatively few parts and when assembled is rigid and not liable to get out 20 of order. It will also be apparent the device is easy to assemble which facilitates manufacture.

Having thus set forth the nature of my invention, what I claim is:

5 1. An attachment plug comprising an insulating body provided with a central projection at its inner end and spaced contact slots piercing said body, a screw shell around said projection and open at both 30 ends, means for securing the shell to the body, a contact in one of said slots electrically connected with said shell, an insulating button in the other end of the shell abutting the projection on the body and 35 provided with a shoulder on the outer walls thereof, the end of the shell being spun over this shoulder to retain the button in position, a central contact extending through said button, and a contact electrically connected therewith located in the 40 other slot in the body member.

2. In a device of the class described, an insulating body member pierced by spaced slots, receptacle contacts in said slots, and 5 said body being provided at its inner end with a projection providing a ledge, means in the body for securing an open ended screw shell on this ledge, an insulating button secured in the other end of the shell 0 and against the projection by the spun over end of the shell, and a central contact carried by said button, said contact and shell having electrical connections with the 50 respective receptacle contacts.

3. A device of the character described comprising an insulating body member having spaced slots extending therethrough, and provided at one end with a ledge surrounding a projection, an open ended shell, 0 means carried by the body for securing the shell on said ledge, a receptacle contact in one of said slots and connected with the shell, an insulating button secured in the open end of the shell against said projection, the inner end of this button being 5

provided with a transverse recess, a central contact extending from the outer end of the button to said recess, and a contact blade extending longitudinally in the recess secured to the central contact and extending into the other slot in the body member. 70

4. A device of the character described comprising an insulating body member having spaced contact slots leading from one 75 end thereof and a ledge at the other end, hollow bushings molded into the body member and projecting above said ledge, an open ended screw shell having a perforated flange fitting over said projecting ends, said 80 ends spun over the flange to retain the shell in position, an insulating button secured in the other end of the shell, a central contact in said button, and contacts carried by the body member in said slots 85 having electrical connections, one with the central contact and the other with the shell.

5. A device of the class described comprising an insulating body member having spaced slots extending longitudinally thereof, and provided at one end with a ledge surrounding a projection, bushings in said body member and projecting above said ledge, an open ended shell provided with a flange having openings to receive said 90 projecting ends and secured to the body by the spun over ends of these projections, an insulating button inserted in the other end of the shell and having an annular shoulder, this button being secured in the 95 shell by the spun over end of the shell, a central contact extending through said button, and contacts in the slots in the body member having electrical connection, one with the shell and the other with the contact 100 in the button. 105

6. An attachment plug comprising an insulating body member provided with spaced contact slots extending longitudinally thereof from its outer end, a screw shell at the 110 inner end of the body and open at its outer end, means for securing the shell to the body, a contact in one of said slots electrically connected with the shell, an insulating button in the open end of the shell and provided with a shoulder on the outer walls 115 thereof, the end of the shell being spun over this shoulder to retain the button in position, a central contact extending through said button, and a contact located in the other slot of the body member and having electrical connection with the said contact. 120

7. An attachment plug comprising an insulating body member provided with spaced contact slots extending longitudinally from its outer end, a screw shell having a flange at its inner end and open at its outer end, means in the body member engaging said flange to secure the shell to the inner end 125 130

of said body, an insulating button in the open end of the shell and provided with a shoulder on the outer walls thereof, the end of the shell being curved over this shoulder to secure the button in the shell, a central contact extending through the button, a contact in one of said slots having electrical connection with the shell, and a contact in the other slot having electrical connection with said central contact. 10

In testimony whereof I affix my signature.

TONJES A. BOTH.
